PAIR OF SPECTACLES

Albert Girouard, Leominster, Mass., assignor to Foster Grant Co., Inc., Leominster, Mass., a corporation of Massachusetts

Application November 18, 1949, Serial No. 6,123

Term of patent 14 years

(Cl. D57—1)

To all whom it may concern:

Be it known that I, Albert Girouard, a citizen of the United States, residing at Leominster, Worcester County, and State of Massachusetts, have invented a new, original, and ornamental Design for a Pair of Spectacles, of which the following is a specification, reference being had to the accompanying drawings, forming part thereof, in which:

Fig. 2 is a top plan view thereof.

The essential features of my design for a pair of spectacles reside in the parts shown by full lines, the design being characterized by the specific manner in which beveling has been applied thereto.

I claim:

The ornamental design for a pair of spectacles, substantially as shown and described.

ALBERT GIROUARD.
